UNITED STATES PATENT OFFICE.

GUSTAVUS A. SCHLECHTER, OF WYOMISSING, PENNSYLVANIA.

DESIGN FOR A COMBINED PENCIL-CLIP AND EYEGLASS-SUPPORT.

48,655.

Specification for Design. Patented Feb. 29, 1916.

Application filed October 12, 1915. Serial No. 55,586. Term of patent 3½ years.

To all whom it may concern:

Be it known that I, GUSTAVUS A. SCHLECHTER, a citizen of the United States of America, residing at Wyomissing, in the county of Berks and State of Pennsylvania, have invented a new, original, and ornamental Design for a Combined Pencil-Clip and Eyeglass-Support, of which the following is a specification, reference being had to the accompanying drawing, forming a part thereof.

In the drawing: Figure 1 is a front elevation of my design. Fig. 2 is a side elevation of my design.

I claim:—

The ornamental design for a combined pencil clip and eye-glass support as shown.

GUSTAVUS A. SCHLECHTER.
